UNITED STATES PATENT OFFICE.

CLARENCE E. SEYMOUR, JOSEPH D. SEYMOUR, AND PEARL C. DAVIS, OF MANSFIELD,
OHIO.

DOOR AND WINDOW CASING CONSTRUCTION.

Application filed November 6, 1925. Serial No. 67,313.

This invention relates to door and window casing construction, the primary object of the invention being to provide a novel form of casing wherein an exceptionally rigid connection will be had between the side members of the casing and the head member to insure against sagging of the casing.

Another object of the invention is to provide a construction whereby a complete side of a window casing, door casing or the like may be assembled in shops as units and delivered to the jobs where they may be nailed in their openings, as a whole, thereby eliminating the handling and fitting of numerous pieces on the job.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a front elevational view of a window casing constructed in accordance with the invention.

Figure 2 is a sectional view taken on line 2-2 of Figure 1.

Figure 3 is an elevational view of a door casing constructed in accordance with the invention.

Figure 4 is a longitudinal sectional view through one of the side members of the casing.

Figure 5 is a sectional view through a window casing.

Figure 6 is a perspective view illustrating disconnected sections of the casing.

Referring to the drawings in detail, the window casing which is shown more particularly by Figure 1 of the drawings includes side casing members 5, a head casing member 6, a sill 7 and an apron 8, the upper and lower ends of the side casing members being rabbeted as at 9 to fit with in the correspondingly-shaped rabbet 10 formed in the head section 6 and the apron 8 of the sill so that close fits will be provided between the various sections of the casing.

Secured along the side edges of the casing are sections known as back band sections

12, the upper back band section 13 extending along the upper edge of the head casing section 6, where it has its ends beveled to meet the beveled ends of the back bands 12.

A lower back band section 14 is provided at the base of the window and also has beveled extremities engaging the beveled extremities of the back bands 12.

The sill which is indicated at 7 is cut away adjacent to its ends as shown at 15 allowing the sill to fit closely within the side casing section 5. It might be further stated that the back bands 12 and 13 are formed with longitudinal flanges 16 overlying portions of the side casing sections, head casing sections and apron of the sill to provide a finishing strip between the back band sections and adjacent sections of the casing.

In the application of the invention, in the construction of a door, it will be seen that the side casing sections 17 have their upper and lower ends rabbeted as at 18 which rabbets provide enlargements to fit within the rabbeted section 19 or head section of the casing.

In this form of the invention the back bands which are indicated at 20 are also formed with flanges 21 to finish off the connection between the casing and back bands.

From the foregoing it will be obvious that due to this construction, a complete window or door casing will be assembled in the shops, and carried to the job to be positioned, eliminating the necessity of setting up the structure on the job.

We claim:

In a joint for connecting the vertical and horizontal sections of a frame, the horizontal section having a rabbet extending from one end and disposed adjacent to the lower edge thereof said rabbet defining a rib and shoulder at one end of the rib, the rib being of a length of less than the length of the shoulder section, the vertical section having a rabbet formed across one end thereof defining a rib to be fitted in the rabbet of the shoulder section, the ribs adapted to interlock to secure the vertical and horizontal sections together.

In testimony that we claim the foregoing as our own, we have hereto affixed our signatures.

CLARENCE E. SEYMOUR.
JOSEPH D. SEYMOUR.
PEARL C. DAVIS.
